(57) CLAIM

I claim the ornamental design for measuring wheel, as shown.

DESCRIPTION

FIG. 1 is a front perspective view of a measuring wheel according to an embodiment of the invention with a handle in a retracted position.

FIG. 2 is a back perspective view of a measuring wheel according to an embodiment of the invention.

FIG. 3 is a top view of a measuring wheel according to an embodiment of the invention.

FIG. 4 is a bottom view of a measuring wheel according to an embodiment of the invention.

FIG. 5 is a first side view of a measuring wheel according to an embodiment of the invention.

FIG. 6 is a front view of a measuring wheel according to an embodiment of the invention; and,

FIG. 7 is a second side view of a measuring wheel according to an embodiment of the invention.
